(57) **CLAIM**

The ornamental design for a fish gripper, as shown and described.

DESCRIPTION

FIG. 1 is a perspective view of the fish gripper of the present invention.

FIG. 2 is a side view of the fish gripper illustrated in FIG. 1.

FIG. 3 is opposite side view of the fish gripper illustrated in FIG. 1.

FIG. 4 is front view of the fish gripper illustrated in FIG. 1.

FIG. 5 is rear view of the fish gripper illustrated in FIG. 1.

FIG. 6 is a top view of the fish gripper illustrated in FIG. 1; and,

FIG. 7 is a bottom view of the fish gripper illustrated in FIG. 1.

The evenly spaced broken lines shown in FIGS. 1-7 represent portions of the fish gripper that form no part of the claimed design. Dot-dash broken lines depict a boundary between claimed and unclaimed portions of the fish gripper.

1 Claim, 6 Drawing Sheets(56)
